COMBINATION FENDER AND ANDIRON

John B. Turner, Norwich, N.Y., assignor to Bennett-Ireland, Inc., Norwich, N.Y., a corporation of New York

Application June 26, 1958, Serial No. 51,561

Term of patent 14 years

(Cl. D81—5)

Figure 1 is a front elevation of the combination fender and andiron incorporating my new design;

Figure 2 is a top plan view of the combination; and

Figure 3 is a side elevation thereof.

Figures 1 and 2 of the drawing are shaded to show contrast.

I claim:

The ornamental design for a combination fender and andiron, as shown and described.
